FREE PISTON PNEUMATIC HAMMER

Samuel Ohlsson, Wilkinsburg, Pa., assignor to
Robert A. Rundle, Edgewood, Pa.

Application April 18, 1935, Serial No. 17,001

13 Claims. (Cl. 125—34)

This invention relates to free plunger hammers and has for an object the production of such a hammer which eliminates the necessity of employing expensive and elaborate auxiliary equipment such as is essential in connection with the use of a modern pneumatic hammer.

A further object is to produce a hammer of the pneumatic free plunger type wherein the free plunger responds to variations in fluid pressure which are occasioned by mechanisms located within and forming a unitary part of the hammer.

A further object is to produce a hammer of the class defined which is comparable, from the standpoint of utility and effectiveness, with present day pneumatic hammers, but which is cheaper to build, install for operation, and operate than such hammers.

A further object is to produce a new and improved procedure or method of operating the impact plunger of a hammer having the functional characteristics of the modern free plunger pneumatic hammer.

These and other objects which will be made more apparent by the further description of my invention are attained by means of a hammer embodying the features and characteristics disclosed by the accompanying drawings.

In the drawings:

Figure 1 is a longitudinal sectional view of a hammer embodying my invention;

Fig. 2 is a sectional view along the horizontal plane 2—2 of Fig. 1;

Figs. 3—8 inclusive are diagrammatic views disclosing various positions occupied by the principal moving parts of the hammer during one complete cycle of operation; and

Fig. 9 is a more or less diagrammatic view of a hammer embodying my invention and illustrates a modification of structural details which may be employed in connection therewith.

The hammer illustrated in Figs. 1 and 2 of the drawings as an embodiment of my invention includes an impact plunger 10 which is located within a cylinder 11 formed within the barrel 12 of the hammer and which has many of the characteristics of the free piston of the modern pneumatic hammer and responds to variations in fluid pressure at its rear end. The plunger 10 reciprocates within the cylinder 11 and on its forward stroke is projected at a high velocity against an impact tool or bit 13 of such a tool. The variations in the fluid pressure within the cylinder 11, at the rear end of the plunger 10, are occasioned by a power driven piston 14 which is located within the rear end of the cylinder 11.

The arrangement of the apparatus is such that during each cycle of operation air is trapped within the cylinder between the forward end of the piston 14 and the rear end of the plunger 10 and is slightly compressed by the forwardly moving piston 14 and to a degree necessary to overcome the friction of rest and the inertia of the plunger 10. As soon as the plunger 10 starts to move forward, i. e., in the direction of the arrow of Fig. 2, its resistance to motion is materially decreased because the friction of motion is materially less than the friction of rest, and consequently the plunger will, in responding to the pressure of the trapped air behind it, accelerate in velocity at substantially the same rate as the piston 14. Thus it is apparent that the plunger 10 is operatively coupled to the piston 14 by what may be termed a variable air coupling and, while the plunger accelerates in speed at a rate substantially equal to the rate of acceleration of the piston during the first portion of the piston stroke, the deceleration of the piston 14—during the latter portion of its stroke—does not affect the speed of the plunger 10 as it moves toward the impact tool preparatory to delivering a blow to that tool. As will be more fully described, the plunger 10 completes its impact stroke at substantially the maximum velocity of the piston 14, with the result that, during normal operations, it is projected against the tool bit at a projectile-like velocity.

A characterizing feature of my invention is that air is first trapped within the cylinder 11 and then discharged from the cylinder during the forward movement of the piston 14, with the result that the piston completes a portion of its forward stroke without doing any work other than that required to expel previously trapped air from the cylinder 11. The return stroke of the piston 14 is also characterized by the fact that the space within the cylinder 11, between the rear end of the plunger and the forward end of the piston, is first cut off from communication with the atmosphere and then open to the atmosphere. Under such conditions the returning piston 14 tends to create a vacuum or a substantial rarefaction of the trapped air as it starts on its return stroke, with the result that the plunger 10, responding to the preponderating pressure of the atmosphere on its forward end, follows the piston throughout a substantial portion of the piston's return travel; and then communication between the atmosphere and the interior of the cylinder is again established by the piston uncovering an air port, and the piston

completes its return stroke without doing any work other than drawing a full charge of air into the cylinder preparatory to a repetition of the cycle here described.

Referring more specifically to the drawings, the barrel 12 of the hammer, which encloses the cylinder 11 and the piston 14 and which also forms a guide for the reciprocations of the plunger 10, may be said to constitute the body portion of the hammer. As shown in Figs. 1 and 2, a breech portion 15 is secured to the barrel by means of a ring nut 16, which engages a flange 17 formed near the rear end of the barrel and operates to draw a threaded annular flange 18 of the breech portion, against the rear face of the flange 17 and thus position the breech with relation to the barrel. It will, of course, be understood that any suitable means for securing these parts together may be employed, since this feature forms no part of my present invention, except insofar as it is essential as a part of an operative structure which may be manufactured at a reasonable cost. An inspection of Figs. 1 and 2 discloses that the annular flange 18 surrounds and seats on a rearward extension of the barrel, which projects beyond the flange 17. This detail is desirable because it provides a cylinder having an internal bore free from joints and seams; it, however, is not essential.

The breech portion 15 encloses and constitutes a casing for the operating mechanism of the piston 14. In the hammer illustrated, a power driven crank shaft 19 is enclosed by and is mounted in suitable bearings provided within the breech portion. The crank pin 20 is operatively connected to the piston 14 by means of a piston rod 21 and the crank shaft is provided with suitable balancing discs 22 for counterbalancing the weight of the crank pin and the associated portion of the piston rod.

In Fig. 2 of the drawings, the crank shaft 19 is shown operatively coupled to a motor driven flexible shaft 23, which as is usual, is enclosed by a flexible casing 24. This particular feature of the disclosure does not constitute an important part of my invention, since it will be understood that any convenient means may be employed for driving the crank shaft at the desired speed, and that consequently any suitable means may be utilized for operatively connecting the crank shaft 19 to a driving motor. I, however, prefer to employ an electric motor as the source of power and it will be apparent that various positional relations between the shaft 19 and the driving motor may be employed.

Communication between the interior of the cylinder, or the portion thereof intermediate the plunger 10 and the piston 14, is controlled by the plunger 10 and piston 14 operating in conjunction with a valve 25 which moves synchronously with the crank shaft 19. In Fig. 2, the valve 25 is shown as a sleeve valve which, in effect, constitutes an extension of the crank shaft 19 and is journaled in a sleeve bearing 25a. The bearing 25a is supported by and enclosed in the breech portion 15 and constitutes a ported casing for the valve 25. The valve 25 is provided with two ports 28 and 29 (see Fig. 3) which cooperate with a port 26 formed within the sleeve bearing 25a for the purpose of alternately establishing and cutting off communication between a passage 27 and the interior of the sleeve valve 25.

The interior of the sleeve valve communicates directly with the atmosphere through ports formed in a cap nut 30 secured to the breech por-

tion and forming an end enclosure for the sleeve valve. As shown in the diagrammatic views of Figs. 3 to 8, the ports 28 and 29 of the sleeve valve 25 are located in substantially diametrically opposed positions, with relation to the center of rotation of the sleeve valve, and the port 28 is substantially larger than the port 29, i. e., its peripheral length is substantially greater than that of the port 29.

The diagrammatic views above referred to also disclose the relationship of the ports 28 and 29 with the port 26 during the operation of the hammer. The passage 27 is always in open communication with the port 26 and communicates with the interior of cylinder 11 through two spaced branch passages 27a and 27b. Both the piston 14 and the plunger 10 have a tight sliding fit with the wall of the cylinder 11 and, with the arrangement of the branch passages illustrated, the plunger 10 and the piston 14 cooperate with the valve 25 in controlling communication between the interior of the cylinder and the atmosphere. A manually operated valve 31 may also be employed for controlling a communication between the portion of the cylinder 11 intermediate the plunger and the piston and the atmosphere. This valve operates as a throttle valve and its function is to establish communication between the interior of the cylinder 11 and the atmosphere independently of the position of the ports 28 and 29 of the valve 25 with relation to the port 26.

As shown in Fig. 1, valve 31 consists of a slide valve located in a passage suitably formed within the breech portion 15 and it is adapted to control communication between a port 32, which is always open to the atmosphere, and a port 33, which, by means of a passage 33', communicates with the passage 27 (Fig. 2). The bore in which the valve 31 is located is suitably countersunk to provide a shoulder which constitutes a seat for a coil spring 34 surrounding the valve 31 and acting between the seat and a shoulder formed by a valve extension 31' of increased diameter. The spring acts to hold the valve 31 open, i. e., in a position establishing direct communication between the ports 32 and 33, in which position the extension 31' projects beyond the confines of the valve enclosing bore and is engaged by a valve actuating trigger 35 pivotally mounted on the breech portion 15. From this it will be apparent that the spring 34 not only acts to hold the valve in the so-called open position, but also acts to hold the extension 31' against the trigger. As will hereinafter be more fully described, when the valve 31 is in the position illustrated in Fig. 1, the passage 27 is always in free communication with the atmosphere, consequently the reciprocations of the piston 14 will not control the movements of the plunger 10.

The diagrammatic views of Figs. 3 to 8 disclose various positions occupied by the parts at different intervals during a complete cycle of operation. In describing the operation illustrated by these views the valve 31 is assumed to be closed. In Fig. 3, the piston 14 has reached its rearmost position and the port 29 of the valve 25 has just moved out of register with the port 26, thus cutting off communication between the atmosphere and the space within the cylinder 11 intermediate the forward end of the piston 14 and the rear end of the plunger 10, which space for convenience of description, is designated S in the diagrammatic views. In this portion of the cycle the plunger 10 is in its rearmost position

and an annular shoulder 36 formed on the plunger near its forward end, is in engagement with an annular shoulder 36a formed on the interior surface of the barrel 12 by enlarging the bore at the forward end of the barrel. As the crank pin 20 continues its movement in the direction of the arrow of Fig. 3, the piston 14 is advanced on what may be termed its forward or compression stroke and its closes the branch passage 21b, thus shutting off the space S from the passage 27, because in this position of the piston the plunger 10 is either just starting to move forward or is still in its rearmost position, but in any event, it is in such a position as to close the branch passage 21a. This position of the parts is illustrated in Fig. 4.

During this portion of the cycle the advancing piston 14 is accelerating in speed and the acceleration increases until the piston rod 21 reaches a position substantially as disclosed in Fig. 5, wherein the line defined by the center of the crank pin and the center of the piston pin 31 is tangent to the circle defined by the center of the crank pin in its rotation. During this portion of the cycle the plunger 10, moving in response to the pneumatic pressure within the space S occasioned by the advancing piston 14, has reached the end of its stroke or has been projected at a high velocity against the tool 13.

From the diagrammatic views and also from the previous description it will be apparent that the maximum pressure which can be developed within the space S by the advancing piston 14 is only that which is necessary to overcome the friction of the plunger 10 and the inertia effect occasioned by the mass of the plunger. When, however, the piston 14 is in the position illustrated by Fig. 5, the rear end of the plunger has uncovered the branch passage 21a and has thus established communication between the space S and the passage 27. In this position the port 28 of the valve 25 is just starting to uncover the port 26, or in other words, the parts are all in the positions such that a further movement will establish free communication between the space S and the atmosphere. As the piston 14 continues its forward movement or as the crank pin 20 moves from the position illustrated in Fig. 5 to the position illustrated in Fig. 6, the port 28 remains in register with the port 26, due to the peripheral length of the port 28. From this it is apparent that as the piston 14 advances from the position shown in Fig. 5 to that shown in Fig. 6, its only function is to expel the air previously trapped in the space S. However, as the piston arrives at the extreme end of its forward stroke the port 28 moves out of register with the port 26, thus again cutting off communication between the space S and the atmosphere. This relation of ports 26 and 28 is illustrated in Fig. 6.

The continuing movement of the crank pin 20 starts the piston back, but this rearward movement of the piston tends to create a vacuum—or a partial vacuum—within the space S and the degree of the vacuum thus produced will depend upon the frictional and inertia forces to be overcome in moving the plunger 10 rearwardly. That is to say, the return or rearward movement of the plunger 10 is occasioned by the preponderance of atmospheric pressure—acting at the forward end of the plunger—over the sub-atmospheric pressure within the space S, consequently the direct effect of the piston 14 in moving the plunger rearwardly will depend upon the degree of

vacuum, within the space S, necessary to overcome the above mentioned forces.

Figure 7 diagrammatically illustrates the positions of the parts as the crank pin, moving in the direction of the arrow, moves the piston 14 through the accelerating portion of its rear or return stroke. There the port 26 is closed by the valve 25 and in addition the branch passages 21a and 21b are both closed by the parts operating within the cylinder 11. As a result of this relationship of the parts, the so-called variable air coupling tends to, and does function to move the plunger 10 with the piston 14.

Figure 8 illustrates positions of the parts such that the rearwardly moving piston 14 is just starting to open the branch passage 21b and the port 29 is in register with the port 26 and is moving to establish full and free communication between the passage 27 and the atmosphere. It is, therefore, apparent that a further movement of 20 the piston 14 toward the rear end of its stroke, will establish full and free communication between the space S and the atmosphere. Fig. 8 also discloses that in the portion of the cycle there illustrated, the rearward movement of the 25 plunger 10 has been stopped by the engagement of the shoulder 36 with the shoulder 36a and that consequently, throughout some portion of the piston's rearward movement, the space S has been enlarged and the degree of vacuum existing 30 therein increased by this enlargement. As soon as the passage 21b is uncovered by the piston, atmospheric pressure will again be established in the space S. As the parts move from the positions shown in Fig. 8, to the positions shown in 35 Fig. 3, the cycle of operation is completed, but during this period, the space S is retained in open communication with the atmosphere through the branch passage 21b, the passage 27, the port 26, the port 29, the interior of the valve 25 and the 40 ports of the cap nut 30. As previously described, as the parts move to the positions illustrated in Fig. 3, the port 29 moves out of register with the port 26, thus trapping a charge of air within the space S and the communicating passages 45 formed within the hammer and the breech portion thereof.

A comparison of Figures 3 and 6 discloses that the travel of the piston 14 is considerably greater than that of the plunger 10. In the illustrated 50 embodiment the throw of the plunger is approximately half that of the piston, the stroke of the plunger being limited by the tool 13 and by the shoulders 36 and 36a. This difference in stroke or throw of the plunger and piston is an important feature of my improved hammer, since it permits the plunger to lag behind the piston on the return stroke without destroying the necessary synchronous operation of the two elements. This permissible lag makes it possible to reduce 55 the speed of the return stroke of the plunger—i. e., the plunger's movement to its rearmost position—and thus reduce the impact between the shoulders 36—36a. In other words, the fact that the plunger's backward travel is substantially 60 less than (approximately half of) the piston's backward travel makes it possible for the plunger to travel much more slowly on its backward stroke than the average speed of the piston, consequently, the plunger on coming to rest in its rearmost 65 or initial position, will not impose excessive jars and shocks on the hammer, on the operator's hand and the operating parts of the hammer. On the other hand, the short travel of the plunger permits it to arrive at its initial position in plenty 70

of time to fully respond to the forward impelling forces occasioned by the forward movement of the piston 14 and to effectively employ those forces in striking a blow, as for example, on the 5 tool bit 13.

An analysis of the cycle of operation as illustrated by Figures 3-8, discloses that the operation of the plunger 10 closely approximates the 10 operation of the free piston in the modern pneumatic hammer. As the piston 14 of the hammer illustrated, moves through the accelerating portion of its forward stroke, it starts to compress the air trapped as above described. As it closes 15 the passage 27b, this compressing action on the air thus trapped within the space S is more effective, but in any event, the degree of pneumatic pressure built up within the space S will not substantially exceed that necessary to overcome the friction of rest and the inertia of the 20 plunger. As soon as the plunger starts its forward movement, the frictional resistance is reduced, because the friction of motion is less than the friction of rest, consequently, the plunger 10 will move forward with at least the same acceleration 25 as the piston 14 and it is apparent that the expansion effect of the compressed air may impart a greater acceleration to the plunger 10 than is imparted to the piston 14 by the crank pin as 30 the crank pin moves from the position shown in Fig. 3 to that shown in Fig. 5. In any event, the arrangement of parts is such that the advancing plunger 10 will deliver its blow to the tool 13 while it is moving under conditions established 35 within the working passages of the hammer by the piston 14 as that piston moves forwardly at its greatest speed.

It will also be apparent that the force of the blow delivered by the plunger 10 will depend 40 upon the mass of the plunger and the final velocity of the plunger. It will also be apparent that the final velocity of the plunger is directly dependent upon the maximum velocity of the piston 14 as it traverses its forward stroke. It will therefore be apparent that the force of each blow delivered by the hammer may be varied by varying 45 the number of reciprocations, per unit of time, of the piston 14, and may be increased by speeding up the motor driving the shaft 19. Thus, the force of each blow and the power output of the hammer, per unit of time, may be varied by varying 50 the speed of the driving motor.

In Figure 2, and in each of the diagrammatic views, Figs. 3-8, I have shown an auxiliary passage 37' which is adapted to communicate with a port 37a formed in the cylindrical wall of the piston 14 and thus establish communication between the space S and the atmosphere under a 55 condition which may be encountered at the time 60 of starting the hammer. In this connection, it will be understood that the rear of the piston 14 is always in direct communication with the atmosphere through the valve 25 as is shown in Fig. 2. If, at the time of starting, the plunger 10 is at the forward end of its stroke or in the position illustrated in Figs. 5 and 6 and the piston 14 is at the rear end of its stroke or in the position illustrated in Figs. 3 and 8, an excessive 65 volume of air will be trapped within the hammer cylinder by the forwardly moving piston, with the result that an excessive pressure will be produced unless some means is employed for establishing normal operative conditions within the hammer cylinder. If we, therefore, assume that 70 75 at starting, the piston and plunger occupy the

positions above defined, it will be apparent that the forwardly moving piston will compress the trapped air and that the plunger moving in response to any excess pressure which may be thus produced, will place the passage 37' in direct 5 communication with the space S so that the excess pressure thus developed is exhausted to the atmosphere when the port 37a of the piston registers with the passage 37'.

This forward movement of the piston is only 10 resisted by the tool 13 which is loosely held in place, consequently, unless the tool is applied to the work with unusual force, normal conditions are immediately established within the cylinder and normal operation then follows. 15

The first operation of starting the hammer is of course the starting of the driving motor and where the hammer is provided with a throttle valve, such as the valve 31, which is normally held open, the reciprocations of the piston 14 20 will have no effect on the plunger except possibly the momentary effect of moving it against the tool 13, since the passage 27 is in open communication with the atmosphere and the functioning of the valve 25 therefore has no effect in trapping air within the hammer. It will, however, be apparent that even though the passage 27 is maintained in open communication with the atmosphere by the open throttle valve 31, the advancing piston 14 can only move into metal to 30 metal contact with the plunger 10 at the extreme end of its forward stroke and then only when the plunger is in such a forward position as to uncover the branch passage 27a since in all other 35 positions of the plunger and the piston, these parts themselves close off communication between the space S and passage 27 and consequently providing an air cushion between the plunger and piston which will prevent direct contact and consequent injury to either at the time of starting up. 40

As the throttle valve 31 is closed by the manipulation of the trigger 35, the port 33 is first restricted and then completely closed, consequently, the degree of pressure generated within the space S by the advancing piston can be controlled, to 45 some extent, by the throttle valve and in this way the force of each blow struck by the plunger 10 can be controlled, to some extent. Here again, the difference in plunger and piston travel is of importance. It will be apparent that variations in the position of the throttle valve 31 will occasion variations in the maximum air pressure produced within the space S by the forwardly moving piston 14 and that consequently, where the throttle is partially open, the plunger moving 55 in response to the pressure in space S may, in effect, lag behind the piston and thus strike a blow considerably lighter than under normal operating conditions, where the valve 31 is fully closed. From the foregoing it is apparent that 60 the valve 31 is in effect a by-pass valve, since it bypasses atmospheric pressure around the valve 25 into the passage 27 and thus into the space S of the cylinder 12.

In Fig. 9, I have shown a further modification 65 of the apparatus in which some structural details are varied. This figure corresponds generally to Fig. 2 except the plunger limiting shoulder is located at the rear instead of at the front of the plunger. The plunger is provided with a 70 rearward extension 10a which forms a shoulder 36b near the rear end of the plunger and this shoulder cooperates with a shoulder formed with in the hammer cylinder by an annular inset 40 which may be made of special steel. In other 75

respects, the structural details are substantially as shown in Fig. 2.

In Fig. 9, and also in Fig. 2, I have shown a passage 41 which establishes direct communication between the external atmosphere and the interior of the hammer in front of the plunger 10. It will, of course, be apparent that one or more of such passages may be employed and that they are desirable because the more or less loose fit around the tool bit 13 may not be adequate to maintain atmospheric air pressure ahead of the plunger 10 at all times during operation.

From the foregoing, it will be apparent that my invention makes it possible to obtain all the advantages of the modern free piston pneumatic hammer without the necessity of employing the expensive equipment such as air compressors, air tanks, air lines, air valves, etc. which are necessary parts of the modern air hammer equipment. It will also be apparent that hammers embodying my invention are just as convenient for use as the modern air hammer, since, while it is necessary to employ a flexible shaft to drive the hammer—where the driving motor is not a unitary part of the hammer—or to employ an electrical lead-in and outlet—where the driving motor is a unitary part of the hammer—nevertheless, these connections are less cumbersome than the ordinary air hose made necessary by the use of the usual types of pneumatic hammers. In addition, even where a separate motor is employed, the flexible shaft need not be as long as the usual air hose, since the motor equipment is relatively small and therefore can be assembled as a part of a portable unit, and may be placed adjacent to the work in hand.

While I have described but one method of procedure in connection with the illustrated apparatus, it will be apparent that the separate steps of this method may be varied and also that the structural details of the apparatus illustrated may be varied without departing from the spirit and scope of my invention as defined by the appended claims.

45 What I claim as new and desired to secure by Letters Patent is:

1. In combination in a pneumatic hammer, a cylinder, a free plunger and a piston operating within said cylinder, a crank shaft, means connecting said shaft to said piston, driving means for said shaft, a valve operating synchronously with said piston, a piston controlled passage and a plunger controlled passage between said cylinder and said valve, said valve operating in conjunction with said piston and plunger to alternately establish and cut off communication between said cylinder and the atmosphere once during each reciprocation of said piston.

2. In combination in a pneumatic hammer, a cylinder, a free plunger and a piston located in spaced relation within said cylinder, means for positively actuating said piston, a valve operating in synchronism with said piston actuating means, piston and plunger-controlled passages communicating with the passage of said valve, means for limiting the stroke of such plunger to a stroke substantially less than that of said piston, means in addition to said valve for controlling communication between the atmosphere and the interior of said piston, and adjustable means for controlling said last mentioned means.

3. In combination in a pneumatic hammer, a cylinder, a piston and a free plunger located in spaced relation within said cylinder, means for positively reciprocating said piston, means in-

cluding a valve and piston and plunger-controlled passages for controlling communication between the atmosphere and the cylinder space between said piston and plunger, and means for operating said valve in synchronism with said piston.

4. In combination in a pneumatic hammer, a cylinder, a piston and a free plunger located in spaced relation within said cylinder, means for positively reciprocating said piston, means including a valve and piston and plunger-controlled passages for controlling communication between the atmosphere and the cylinder space between said piston and plunger, means for operating said valve in synchronism with said piston, and means for positively limiting the stroke of said plunger to substantially half the stroke of said piston.

5. In combination in a pneumatic hammer, a cylinder, a piston and a free plunger located in spaced relation within said cylinder, means for positively reciprocating said piston, means including a valve and piston and plunger-controlled passages for controlling communication between the atmosphere and the cylinder space between said piston and plunger, means for operating said valve in synchronism with said piston, means for positively limiting the stroke of said plunger to substantially half the stroke of said piston, and adjustable means for delivering atmospheric air to said cylinder around said valve during the operation of said valve.

6. In combination in a pneumatic hammer, a cylinder, a piston and a plunger located in spaced relation within said cylinder, means for positively reciprocating said piston, means including a valve, and plunger and piston-controlled passages for establishing and cutting off communication between the atmosphere and the cylinder space between said piston and plunger during each reciprocation of said piston, means for actuating said valve in synchronism with the reciprocations of said piston, and means for bypassing said valve.

7. In a pneumatic hammer, a cylinder, a free plunger and a piston operatively mounted within said cylinder, means for positively reciprocating said piston within said cylinder, a passageway communicating with said cylinder at spaced positions therealong, and a rotary valve operably connected to said piston and movable therewith, said valve intervening between said passageway and the atmosphere and controlling communication therebetween.

8. In a pneumatic hammer, a cylinder, a piston and a free plunger located within said cylinder, an atmospheric vent passage for establishing communication between the atmosphere and the space between said piston and plunger within such cylinder, a valve for controlling such communication, and means for positively actuating said valve and said piston in timed relation with each other.

9. In a pneumatic hammer, a cylinder, a piston and a free plunger located in spaced relation within said cylinder, an atmospheric vent passage communicating with said cylinder at spaced points therealong for establishing communication between the atmosphere and the space between said piston and cylinder at intervals during the movements of said piston, a valve for controlling such communication and means for positively actuating said valve in timed relation with the operation of said piston.

10. In a pneumatic hammer, a cylinder, a piston and a free plunger located within said cyl-

- inder, an atmospheric vent passage communicating with said cylinder for establishing communication between the atmosphere and the space within said cylinder between said piston and plunger at intervals during the operation of such parts, a valve for controlling such communication, driven means for reciprocating said piston and means for positively actuating said valve in timed relation with the movement of said piston.
- 10 11. In a pneumatic hammer, a cylinder, a piston and a free plunger located within said cylinder, an atmospheric vent passage for establishing direct communication between the atmosphere and the space within said cylinder between said piston and plunger at intervals during the operation of said piston and plunger, a valve for controlling such communication, driven means for reciprocating said piston, means for positively actuating said valve in timed relation with the reciprocation of said piston, and a manually controlled valve for establishing communication between the atmosphere and said passage independently of the operation of said first mentioned valve.
- 20 25 12. In a pneumatic hammer, a cylinder, a pis-

ton and free plunger located within said cylinder, an atmospheric vent passage having a piston controlled port communicating with the interior of said cylinder for establishing direct communication between the atmosphere and the space within said cylinder between said piston and plunger, a valve for establishing and cutting off communication between said passage and the atmosphere, driven means for reciprocating said piston and means for positively actuating said valve in timed relation with the movement of said piston.

13. In a pneumatic hammer, a cylinder, a piston, a free plunger located within said cylinder, an atmospheric vent passage having piston and plunger controlled ports communicating with the space within said cylinder between said piston and plunger, a valve for establishing and cutting off communication between said passage and the atmosphere, driven means for reciprocating said piston, and means actuated thereby for positively actuating said valve in timed relation with the movement of said piston.

SAMUEL OHLSSON. 25
